UNITED STATES PATENT OFFICE.

HUGO B. HEMPE, OF CHICAGO, ILLINOIS.

SATCHEL.

SPECIFICATION forming part of Letters Patent No. 660,270, dated October 23, 1900.

Application filed July 30, 1900. Serial No. 25,316. (No model.)

To all whom it may concern:

Be it known that I, HUGO B. HEMPE, a citizen of the United States, and a resident of Chicago, county of Cook, and State of Illinois, 5 have invented certain new and useful Improvements in Satchels, of which the following is a specification, and which are illustrated in the accompanying drawings, forming a part thereof.

10 This invention relates to the construction of satchels or hand-bags, and has for its objects the simplification and strengthening of the article and the cheapening of the cost of manufacture, a further object being to increase the durability by a better disposition 15 of the material and by so locating the seams as to avoid wear.

The invention consists in the peculiar form of the leather covering for the satchel and the arrangement of its seams and stiffening material, all as hereinafter fully described and as shown in the accompanying drawings, in which—

Figure 1 is an end elevation of a satchel of 25 the type known to the trade as the "cabin" satchel. Fig. 2 is a side elevation of the same. Fig. 3 is a bottom plan view of the same. Fig. 4 is a detail plan section on the line 4'4 of Fig. 1. Fig. 5 is an end view of a bag known to 30 the trade as the "ladies'" satchel, and Fig. 6 is a bottom plan view of the same.

As satchels have ordinarily been constructed the leather cover has been made of a number of pieces—one for each of the ends, one 35 for each of the sides, and one for the bottom—the several pieces being joined at the corners of the bag and at the margins of the bottom. This form of construction has necessitated the cutting of the stiffening material in similar shapes, so that the corners have been 40 peculiarly weak and there has been great tendency of the walls to collapse after short usage. A further disadvantage found in the construction referred to arises from the fact 45 that the seams are located at the angles, the points of greatest wear, and after a short time the stitches become broken and the seams open. An effort has been made to avoid the location of seams at the angles by forming 50 the cover of a single piece; but this effort was not successful, for the reason that the seams were necessarily located at the ends of the

bottom and the construction was open to the further very practical difficulty that it is almost impossible to secure clear leather of sufficient size to make anything but the smaller bags. Neither did this construction admit of the insertion of stiffening used in the larger bags without forming the joints of the latter at the corners. 55 60

In the drawings of this application the sides of the satchel, whether the bag be of large size, as shown in Figs. 1 to 4, or of small size, such as shown in Figs. 5 and 6, are made of two pieces 10 and 11, cut to suitable shape 65 that they may be joined or seamed together at the ends of the bag, as shown at 12 and 13, and their lower edges will underlap its bottom 14, as shown at 15, being mitered at the corners, as shown at 16, and stitched to the 70 bottom 14 along their edges and some distance from the edges of the bottom, as shown at 17. In the larger form of satchel it is customary to use stiffening for the side and end walls, as shown at 18, and in the satchel herein 75 shown and described this stiffening material may consist of two pieces only, one of which is shown at 18 in Fig. 4, each of these pieces extending from midway of one end of the satchel to midway of the other—that is to say, 80 from the seam 12 to the seam 13—and being bent at the vertical corners of the bag, as shown at 19. The stiffening material 18 is secured to the leather cover in any suitable manner, as by the use of cement. 85

The usual lining may be fitted within the satchel, as shown at 20, and as shown presents no novel features. The bottom of the satchel may be armed with studs, as 21, which form feet upon which it may rest, and the 90 upper framework may be made of any desired form.

By the construction described but three pieces are required in forming the outer case, and yet each is comparatively small, so that 95 unless the satchel is of very large size they may be cut from small and consequently comparatively-cheap pieces of leather. The location of the seams at the angles of the bag is entirely obviated, and the stiffening material 100 is of such form and so disposed that there are no joints in it at the vertical angles of the bag, so that their strength is very materially increased.

I claim as my invention—

1. A satchel having the side walls of its outer casing formed of two pieces seamed together only at the ends of the bag and intermediate of its side corners, and each underlapping the bottom of the bag, and being secured thereto at a distance from its side and end edges.
- 5 2. A satchel having the side walls of its outer casing formed of two pieces seamed together only at the ends of the bag and inter-

mediate of its side corners, and each underlapping the bottom of the bag and being secured thereto at a distance from its side and end edges, and having its side walls reinforced by a stiffening formed of two pieces, each extending from one vertical seam thereof to the other.

HUGO B. HEMPE.
